(57) **CLAIM**

The ornamental design for a disposable diaper, as shown and described.

DESCRIPTION

FIG. 1 is a front, right perspective view of a disposable diaper showing my new design;

FIG. 2 is a front elevation view thereof;

FIG. 3 is a rear elevation view thereof;

FIG. 4 is a left side view thereof, with the right side view being identical thereto;

FIG. 5 is top plan view thereof, with the bottom plan view being identical thereto;

FIG. 6 is an enlarged, detail front view of the area 6 circumscribed within FIG. 2; and,

FIG. 7 is a cross-sectional view along line 7-7 of FIG. 6. The portions depicted in FIGS. 1-5 and 7 in dash-dot broken lines of even length are environment and form no part of the claimed design. The portions depicted in FIG. 7 in dot-dash broken lines of uneven length define the unclaimed boundary of the claimed design. The portions depicted in dot-dot broken lines surrounding the detail area of FIGS. 2 and 6 depict boundaries of the area and form no part of the claimed design. The diagonal lines in FIG. 7 are cross-sectional lines.
